US00D744639S

(12) **United States Design Patent**
Aklog et al.

(10) **Patent No.:** **US D744,639 S**
(45) **Date of Patent:** **** Dec. 1, 2015**

(54) **CANNULA TIP**

(71) Applicant: **AngioDynamics, Inc.**, Latham, NY (US)

(72) Inventors: **Lishan Aklog**, Purchase, NY (US);
Michael Glennon, Norwell, MA (US)

(73) Assignee: **ANGIODYNAMICS, INC.**, Latham,
NY (US)

(**) Term: **14 Years**

(21) Appl. No.: **29/507,027**

(22) Filed: **Oct. 23, 2014**

Related U.S. Application Data

(63) Continuation of application No. 14/250,486, filed on Apr. 11, 2014, which is a continuation of application No. 13/084,675, filed on Apr. 12, 2011, now Pat. No. 8,734,374, which is a continuation-in-part of application No. 12/187,121, filed on Aug. 6, 2008, now Pat. No. 8,075,510.

(57) **CLAIM**

The ornamental design for a cannula tip, as shown and described.

DESCRIPTION

FIG. 1 is a perspective view of a cannula tip in accordance with the new design; and,

FIG. 2 is side elevational view thereof.

The broken line showing of parts of the drawings is included for the purpose of illustrating use and environment and forms no part of the claimed design.

1 Claim, 1 Drawing Sheet
